J. H. BRADY.

CAN OPENER.

APPLICATION FILED JUNE 25, 1915.

Patented Apr. 11, 1916.

UNITED STATES PATENT OFFICE.

JAMES HENRY BRADY, OF LOUISVILLE, KENTUCKY.

CAN-OPENER.

1,178,620.

Specification of Letters Patent. Patented Apr. 11, 1916.

Application filed June 25, 1915. Serial No. 36,191.

To all whom it may concern:

Be it known that I, JAMES HENRY BRADY, a citizen of the United States, residing in the city of Louisville, county of Jefferson, 5 and State of Kentucky, have invented a certain new and useful Improvement in Can-Openers, of which the following is a specification.

This invention relates to an improvement 10 in that class of implements, used for obtaining access to containers formed of thin sheet metal, known as can-openers.

An object of this invention is to provide 15 an implement of the class referred to which may be used by an unskilled person with a minimum of effort and a maximum of safety.

A further object is the production of a 20 tool of the class described which will be economical to manufacture and which will be efficient and durable in service.

With the foregoing and other objects in view the invention consists of the novel construction illustrated in the accompanying 25 drawing which forms a part of this specification.

In the drawing wherein similar reference 30 characters designate like parts in the several views, Figure 1, is a perspective view of a can and an opener showing the method of operation; Fig. 2, a perspective view of my improved opener; Fig. 3, a perspective view of a blade; Fig. 4, a sectional view on line 2-2 of Fig. 2; Fig. 5, a plan of a blank 35 from which the blade is formed.

Referring to the drawing the reference 40 numeral —10— designates a handle which may be constructed of any suitable material and of such shape as will best conform to the hand. The blade —11— is secured to, 45 or connected with, the handle by suitable means, and extends beyond the lower end thereof. As illustrated the handle is formed of wood and has two plane parallel surfaces —12, 13—, and is rounded at the top —14— to fit the palm of the hand. The edges slope down to the lower end —15— which is of reduced area, compared with the top. One of the edges —16— is 50 slightly rounded transversely while the other —17— is a plane surface. The blade comprises a web —18— having flanges —19— and —20— extended from the edges thereof and is provided with an oblique cutting edge —21— which is continued on the flanges. In the embodiment of the inven-

tion illustrated, the blade is secured on the plane edge 17, of the handle, by means of a screw —22— which is passed through a perforation —23— in the blade. The blade is 60 secured on the handle in such relationship thereto that the heel —24— of the cutting edge, on the flange 20, lies below the end of the handle such a distance as will allow it to pass through the wall of the container, 65 before the handle comes into contact therewith. Other obvious ways of attaching the blade to the handle will suggest themselves to those skilled in the art, and with a change of 70 material in the handle other methods of attaching the blades will have to be resorted to.

In service the opener is held in the hand, in the same manner as a handle of a screw driver, with the rounded upper end resting against the palm of the hand. The tool is 75 held straight up with the point —25— of the blade resting on the wall of the container a suitable distance from the edge thereof, care being observed to see that the entire cutting edge of the blade will come 80 within the edge of a can, then push the tool straight downward until the lower end of the handle comes into contact with the can, then pull it out. Start second cut at the end of the first cut, etc. (See Fig. 1). 85 After a sufficient number of cuts have been made,—the severed portion may be raised with the point of the opener. It will be observed that the handle makes a cut which comprises a straight portion —26— and lateral extensions —27, 28—. In making the 90 second and subsequent cuts, the point of the blade is inserted in the lateral extension 28 of the previous cut, which serves as a guide for the flange 19 and as a stop to prevent any backward movement of the blade, thereby in securing a cut the full width of the blade at each downward stroke. The shape of the blade allows of the use of a very thin material, sheet metal of approximately 95 .025 of an inch in thickness being preferably used, the flanges serving to give it the requisite stiffness.

It is thought that the many advantages 100 of a can-opener constructed in accordance with the foregoing description may be readily understood, and it will furthermore be evident that changes, variations and modifications may be resorted to without departing from the spirit of the 105 invention, or sacrificing any of its advantages, and I therefore do not wish to re- 110

strict myself to the details of construction herebefore described and as shown in the accompanying drawing, but reserve the right to make such changes, variations and modifications as come properly within the scope of the protection prayed, and

I claim:

In a can opener, a blade having a sloping edge extending forward and upward from the rear edge to the front edge, flanges ex-

tended at an abrupt angle from said edges, and a handle to which said blade is attached and extends longitudinally therefrom, whereby said blade cuts only on a direct longitudinal thrust the front flange 15 making a lateral incision which serves as a guide and an abutment for the rear flange when making a succeeding cut.

JAMES HENRY BRADY.
